UNITED STATES PATENT OFFICE.

MARTIN GALLAGHER, OF PHILADELPHIA, PENNSYLVANIA.

HINGE.

SPECIFICATION forming part of Letters Patent No. 614,098, dated November 15, 1898.

Application filed October 18, 1897. Serial No. 655,048. (No model.)

To all whom it may concern:

Be it known that I, MARTIN GALLAGHER, a citizen of the United States, residing in the city and county of Philadelphia, State of Pennsylvania, have invented a certain new and useful Improvement in Hinges, of which the following is a specification.

My invention relates more particularly to a hinge in which two plates are movably affixed to and revolve one upon the other when a door or shutter to which said hinge may be attached is opened or closed.

It relates especially to and is an improvement upon the hinge invented by me and for which I filed an application in the United States Patent Office on April 23, 1897, Serial No. 633,440, allowed September 13, 1897.

The object of the present improvement is to render more efficient and easy the operation of said hinge by the application of ball-bearings thereto; and it consists of novel details of construction, all as will be hereinafter fully set forth, and particularly pointed out in the claim.

Figure 1 represents a plan view of a hinge embodying my improvement. Fig. 2 represents a side elevation thereof, showing it as applied in double arrangement to an extra heavy door. Fig. 3 represents a perspective view of the portion thereof that is affixed to the door-frame, and Fig. 4 represents a perspective view of that portion that is affixed to the door.

Similar letters of reference indicate corresponding parts in the several views.

My improved hinge consists of horizontally-disposed plates C, (used in either single or double arrangement,) rigidly secured to the vertically-disposed supporting-plate C², or equivalent devices, said plate being secured to the door-frame A by any suitable means, that shown being the screws C'. In case the hinge is used in its single construction the horizontally-disposed plate C may be secured to the door-frame by a screw extension, prong, or such means, as well as by the plate C².

D designates a bracket or flap adapted to be secured to the sides of the door B, to which bracket are attached flat horizontally-disposed plates F, which are pivotally affixed to the horizontally-disposed plates C by means of the pivot-pin c' and the openings f and c².

in said plates, respectively; the plate C being located between the plates F when used in double construction; but, if desired, only one 55 of the plates F may be utilized and the same pivoted directly to the plate C.

The vertically-disposed plate C² is usually concave, and the door-frame made of similar form to receive it, as shown, in order to allow 60 of the free movement of the door-plates F when the door is opened or closed.

In using the hinge it is first attached to the door-frame. Mortises or slots which are the width or depth of the combined thickness of 65 the three or two plates used are formed in the edge of the door, extending parallel to the top and bottom and at right angles to the edges thereof, into which mortises the horizontally-disposed plates are slipped and the same secured to the door by means of the bracket D and its screws D'. The hinge can also be secured to the upper and lower edges of said door without in the least affecting its practicability.

The above forms the subject-matter of my former application referred to.

My present improvement consists in forming channels, annular grooves, or ballways c upon the upper and lower faces of plates C, 80 as well as upon the inner faces of the plates F, as designated by F', to correspond with grooves c, and placing in said grooves balls or spheres F², Figs. 1 and 2, upon which spheres plates F revolve or turn, it being obvious that 85 all friction is thus reduced to a minimum and the swinging of the door or shutter or other article to which the hinge is attached is rendered absolutely free and unhampered and the strength or exertion to be applied in opening or closing the door is of the smallest. 90 The said spheres not only operate as perfect ball-bearings or antifriction means, but they also act as efficient and perfect pivots, holding the fixed and movable parts of the hinge 95 assembled and in juxtaposition, enabling the hinge to be used without the ordinary pivot-pin as efficiently as with one and thereby performing a double function at one and the same time, which are the essential and novel 100 results of my improvement.

In extra heavy doors the hinge may be used in double arrangement, as shown in Figs. 2, 3, and 4, and provided with and connected by

suitable scrollwork, which imparts to the same the appearance of being one hinge.

Any suitable material can, of course, be used in the construction of my improved hinge; but I prefer the best of metal, known as "gun-metal," particularly in making the plates C, for upon them the whole weight of the door bears, and the grooves F' are cut as close to the edges of the plates as possible, in order to obtain the largest bearing-surface permissible.

Having thus described my invention, what I claim as new, and desire to secure by Letters Patent, is—

15 In a door-hinge, the combination with a vertically-disposed plate adapted to be secured to a door-frame, and flat horizontally-disposed plates secured thereto and having

annular grooves or ballways in their upper and under surfaces, of a bracket adapted to 20 be secured to the sides of a door, flat horizontally-disposed plates secured in the bracket, adapted to be seated in a mortise in the edge of the door, and spaced to embrace the horizontal plates, respectively, of the door-frame 25 plate and having annular grooves or ballways contiguous to the grooves or ballways of the plate embraced thereby, and bearing-balls in said grooves or ways whereby the door member of the hinge is antifrictionally and pivotally connected to the door-frame member, substantially as described.

MARTIN GALLAGHER.
